D. COPE.

Cask Filler.

No 103,845.

Patented June 7, 1870.

United States Patent Office.

DAVID COPE, OF LIVERPOOL, ENGLAND.

Letters Patent No. 103,845, dated June 7, 1870.

IMPROVEMENT IN CASK-FILLERS.

The Schedule referred to in these Letters Patent and making part of the same.

To all whom it may concern:

Be it known that I, DAVID COPE, of Liverpool, in the county of Lancaster, England, have invented a certain new and Improved Cask-Filler; and I do hereby declare that the following is a full and exact description thereof, reference being had to the accompanying sheet of illustrative drawings which form part of this specification, and to the letters and figures marked thereon, that is to say—

Heretofore the filling of casks and like utensils of capacity from stock-tanks and vessels generally has been attended with considerable loss in consequence of overflowing.

To prevent waste from overflowing, and to render the operation of filling casks or utensils (with such liquids as oil and beer) less dependent on the attention of workmen are the main objects of my invention.

For these purposes I provide a filler or apparatus, which, when attached to or placed on a cask, fits tightly to the outer surface thereof around the bung-hole, and effectually prevents escape of liquid through between it and the cask. Such apparatus is also provided with a spout to convey away and save any liquid that may overflow to a gutter leading to a tank or vessel, or directly to a vessel.

Figure 1 is a perspective view of my said filler, the fastening-nut being run back or left slack on the screw.

Figure 2 is a side elevation, part of a cask and gutter being shown.

Figure 3 is a plan view.

In these views like letters denote the same parts. *a* is the body of the filler, here shown fitted with check-pieces *b*, whereby the whole can be suspended over a pulley, or otherwise, and easily moved.

c, spout.

d, flexible packing-piece formed of leather stuffed with horse-hair, felt, closely compacted woven fabrics, or other springy substance. This piece accommodates itself to the form of the cask, and is caused to fit closely thereto by a fastening-clamp.

The said fastening-clamp consists of three parts, *e* being a hooked piece which is passed into the cask through the bung-hole, *f* being a screwed stem, and *g* a locking-nut with a handle.

h is a guide-bar for the stem *f*, and

i, a spring which bears on the cask, and equalizes the pressure on *d*.

j shows part of a cask, and

k gutter to convey away any liquid that overflows.

In adjusting this apparatus on a cask, before passing the filling-nozzle or ordinary filler into the bung-hole, or pouring the liquid into *a*, it is simply necessary to pass *e* through the bung-hole, and turn it into the position under the stave shown by dotted lines in fig. 2, and to screw down *g* on *f* until it reaches *h*, as also shown by dotted lines.

By doing so the packing-piece *d* is compressed, the pressure being distributed by *i*, and the whole made to fit tightly.

A modification of my said filler is illustrated by Figures 4 and 5,

Fig. 4 being a longitudinal section, and

Fig. 5, a plan view.

l is the body of the filler.

m, suspender.

n, spout.

o, packing-piece.

p, part of cask.

q, spiral springs placed in a recess in *l*, and pressing against the rigid backing *r* of the packing-piece *o*. The force with which these springs act is equivalent to the weight of the apparatus; hence it is usually made of considerable weight.

This modification adapts itself to the form of the cask without special fixing or clamping, hence it is only necessary to place it on the cask around the bung-hole for use; in practice I prefer the modification first above described.

It will be obvious that by using the above apparatus one workman will be enabled to attend to the filling of a number of casks. Should any of them overflow no loss will be sustained, as the liquid will be conveyed along the spout, thence to the gutter or other vessel.

Having now described the nature of my said invention, and particularized the same by two modifications, I would have it understood that,

What I claim is—

The combination of the body *a*, spout *c*, packing-piece *d*, and fastening-clamp *e f g*, in the manner and for the purpose set forth.

In testimony whereof I have hereunto set my hand this 4th day of March, in the year of our Lord one thousand eight hundred and seventy.

DAVID COPE.
